WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-CENTRALIZING MECHANISM.

1,164,194.

Specification of Letters Patent. Patented Dec. 14, 1915.

Application filed July 3, 1915. Serial No. 37,845.

To all whom it may concern:

Be it known that I, WILLIAM KELSO, a citizen of the United States, residing at Pittsburgh, in the county of Allegheny and State of Pennsylvania, have invented certain new and useful Improvements in Coupling-Centralizing Mechanism; and I do hereby declare the following to be a full, clear, and exact description of the invention, such as will enable others skilled in the art to which it appertains to make and use the same.

My invention relates to the construction of appliances for yieldingly maintaining a car coupler in a centralized position.

The principal object of the invention is to provide a durable and efficient centering device that may be readily assembled and disassembled without the use of special tools. This object, generally stated, is effected by mounting upon the stem of the coupler a frame carrying the yielding means by which said coupler is automatically restored to its normal position in the longitudinal axis of the car after it has been displaced laterally therefrom as the car passes around a curve, said frame comprising detachably connected members and involving separable parts each of which is provided with a hooked portion, said hooked portions being adapted to interlockingly engage each other to thereby prevent lateral separation of the separable frame members.

In the drawings illustrating my invention in its preferred form, Figure 1 is a plan view of a draft appliance embodying my invention, a portion of the coupler head being illustrated in section and a portion of the stem of the coupler being broken away. Fig. 2 is a side elevation of the devices illustrated in Fig. 1. Fig. 3 is a vertical, longitudinal section of the mechanism. Fig. 4 is a transverse section, taken in the plane of the line 4-4, Fig. 1. Fig. 5 is a view in elevation of the forward end of the mechanism, the coupler head and the pivot pin by which the head and stem are connected being omitted. Fig. 6 is a detail plan view of the elements constituting the frame; and Fig. 7 is a detail horizontal section of the forward end of the frame and a portion of the corresponding end of the coupler stem.

In the drawings, 1 indicates the head of a car coupler and 2 indicates the coupler stem. In the construction illustrated the head 1 is connected to the stem 2 by means of a pivot pin 3. The head, therefore, is capable of swinging laterally with respect to said stem which latter is itself designed to be connected to the railway vehicle so as to be capable of swinging or moving laterally in either direction from its normal position in the center of the car. For this purpose the stem 2 may be provided at its rear end with an aperture 4 that is adapted to receive the usual tail pin (not shown) whereby the coupler may be pivotally connected to the railway vehicle through the yielding draft rigging devices. The stem 2 of the coupler is preferably of a well-known type, being provided with an upper branch or plate 5 and a similar lower branch or plate 5, said plates being perforated at their forward ends, as at 6, to receive the pivot pin 3. Interposed between the upper and lower plates 5 is a filler member or spacer 7 which is preferably secured in position by means of a rivet 8 which passes through the branches of the stem, such member 7 being preferably provided with lateral flanges 7^a which serve to maintain in position the longitudinally extending spring 9 that is seated at its rear end upon said member 7. The forward end of the spring 9 bears upon the inner end of the slideable frame upon which is mounted the yielding mechanism for centralizing the coupler stem and the coupler as a whole. Through such frame, which engages the coupler head 1, it serves, as will hereinafter appear, to centralize said coupler head with respect to the coupler stem 2.

Slidably mounted between the plates or branches 5 of the coupler stem in advance of the longitudinally extending spring 9 is a frame which carries spring cups or followers 10 that, respectively, project outwardly in opposite directions beyond the sides of the coupler stem 2 for a sufficient distance to enable them to normally engage the carry iron, draft-sills, or other suitable stationary abutments upon the car or railway vehicle upon which the device is mounted. These spring cups are provided at their inner ends with means for engaging the slideable frame to limit their extent of separation, such

means being preferably formed with flanges 11 which project in a longitudinal direction beyond the sides of the spring cups and which are adapted to engage the slideable frame. The spring cups are normally 5 maintained in a position of maximum separation by means of a transversely extending spring 12 within which a pin or bar 13 may be loosely inserted for the purpose of preventing the spring from being compressed 10 solid and thus being injured.

The frame upon which the spring cups or followers 10 are mounted to reciprocate transversely comprises detachably connected members 14 and 15 each of which is preferably provided with a plurality of integrally attached inwardly extending projections, the mating projections upon the respective frame members 14 and 15 being adapted to have interlocking engagement with each 15 other, as more particularly shown in Fig. 1. The interlocking projections upon the members 14 and 15 are preferably of such a character that some of them coöperate to prevent a relative longitudinal displacement 20 of the members 14 and 15 with respect to each other, while others coöperate to connect said frame members laterally. For the purpose of preventing relative longitudinal 25 movement of the frame members 14 and 15 the member 14 is preferably provided near its forward end with inwardly extending projections 16 each of which is formed at its end with longitudinally extending vertical 30 shoulders 17 between which is a laterally extending lug 18, the said projections 16 being arranged in vertical alinement and being spaced vertically so as to receive between them a key 19 which serves as a means for 35 transversely connecting the separable frame members 14 and 15 contiguous to the coupler head 1. The projections 20 of the frame member 15, which interlock with the projections 16 of the frame member 14, are ar- 40 ranged in spaced relation to correspond to the projections 16 and each is formed at its extremity with a recess or socket 21 which is preferably of tapering form, and which is adapted to receive the correspondingly 45 tapered lug 18 upon the mating projection 16 of the opposed frame member. Each projection 20 is also provided with longitudinally extending vertical faces 22 that respectively engage the corresponding faces 50 or shoulders 17 of the mating projection 16 when the frame members are brought into assembled relation. As more particularly shown in Figs. 5, 6 and 7, each of the projections 16 is preferably provided intermediate 55 of its length with a longitudinally extending vertical shoulder 23, and each of said projections is also preferably fashioned with a transversely extending face or shoulder 25. Each of the projections 20 upon 60 the frame member 15 is similarly fashioned

with shoulders or projections 24 and 26 which correspond, respectively, in form and function to the shoulders 23 and 25 of the projections 16. When the longitudinally movable headed key 19 is in assembled position its shoulders 27 engage the corresponding faces or shoulders 23 and 24 upon the interlocking projections of the members 14 and 15, respectively, the separable frame members being thus detachably connected 75 at their forward ends in such manner that the key 19 may be first removed before such frame members may be separated. The shoulders 25 and 26 upon the frame members are adapted, when the parts are assem- 80 bled, to engage the rear face of the key or link 19 to thus serve as stops for limiting the inward movement of said key. As will be readily understood, the pivot pin 3 by which the coupler head 1 is connected to the 85 stem 2 retains the key 19 in assembled position when the mechanism is in service.

Adjacent to the projections 16 and 20 of the separable frame members 14 and 15, respectively, and preferably on a level with 90 the spaces between said projections, each of said frame members may be conveniently provided with an aperture 28, these apertures being in transverse alinement when the parts are in assembled position. The pur- 95 pose of these openings 28 is to permit a bar or the like to be inserted into the slideable frame so as to force the key 19 forwardly when it is desired to disassemble the parts. To render this operation the more conven- 100 ient the inner face of the detachable key 19 is preferably fashioned with a centrally dis- posed rearwardly extending projection or lug 29 which is in alinement with the open- 105 ings 28 in the separable frame members.

The interlocking projections by which the frame members 14 and 15 are connected laterally are preferably of hook-like form and extend between the upper and lower plates or branches 5 of the coupler stem. The pro- 110 jection 30 on the frame member 14 may, and preferably does, form a seat for the forward end of the longitudinally extending spring 9. The mating hook-like projection 31 on the frame member 15 has overlapping en- 115 gagement with the projection 30, the interlocking faces of said projections being pref- 120 erably inclined, as indicated at 32 and 33, respectively. When the faces 32 and 33 of the hook members are inclined the length of 125 the projections 30 and 31 should be such as to permit the frame members 14 and 15 to move toward each other a sufficient distance to permit the said hooked members to dis- 130 engage by a longitudinal movement of one with respect to the other after the key 19 has been removed and the forward ends of the frame members separated enough to withdraw the lugs 18 of the projections 16 from the corresponding sockets 21 in the projec- 130

tions 20 at the forward ends of the frame members.

Above and below the openings through which the spring cups 10 project, each of the frame members is preferably provided with inwardly projecting, longitudinally extending, flanges 34 and 35, respectively, which not only afford extended bearing and guiding surfaces for the upper and lower faces of the spring cups or followers 10, but which also serve to retain the separable frame members in proper vertical relation with the branches or arms 5 of the coupler stem 2, while permitting the frame to slide or reciprocate freely in a longitudinal direction between said arms. To prevent lateral displacement of the slidable frame with respect to the coupler stem, the side walls of each of the frame members 14 and 15 are preferably extended vertically for a sufficient distance to have overlapping engagement with the outer lateral faces or edges of the plates or arms 5, as particularly indicated at 36 in Fig. 5. Adjacent to the lateral edges of the apertures in the frame members through which the spring cups 10 project, each frame member is formed with vertically extending shoulders 37 which are adapted to engage the flanges 11 at the bases of the respective spring cups to thereby limit the extent of separation of said spring cups.

The forward ends of the frame members 14 and 15 extend into a forwardly contracting pocket 38 in the coupler head 1, and when in normal position, respectively, engage corresponding vertically extending shoulders 39 on said coupler head. It will be seen that the coupler head itself thus serves to prevent the outer ends of the frame members 14 and 15 from separating laterally.

The mode of operation of the device is as follows: When the coupler stem 2 is displaced laterally from its normal position in the longitudinal axis of the car, one or the other of the spring cups or followers 10 moves coextensively therewith, being compelled so to move by reason of the engagement of its flanges 11 with the corresponding stop shoulders 37 upon the adjacent frame member. The other spring cup 10 during this time is prevented from retreating as it is in engagement with the carry-iron, draft-sill or other portion of the car forming a stationary abutment. The spring cups 10 thus approach each other and the transversely extending spring 12, which is interposed between them, is thus compressed. The subsequent expansion of the spring 12 returns the spring cup 10 which has been displaced to normal position, thus also returning the stem 2 of the coupler to a centralized position. When the coupler head 1 rotates upon the pivot pin 3 with respect to

the coupler stem, one or the other of the shoulders 29 on the coupler head, depending upon the direction in which the head moves, acts upon the contacting end of one of the interlocked separable frame members, thus causing the entire frame to execute a rearward sliding movement upon the coupler stem 2. As the longitudinally extending spring 9 is seated upon the member 30 of the slidable frame, such spring is thereby compressed. When the force causing the rotation of the coupler head from its normal position ceases to act the spring 9 is permitted to expand, thus causing the slidable frame to move forwardly on the coupler stem and thereby restoring the coupler head to its central position with respect to the stem 2. While certain features of my invention are especially advantageous when combined with yielding means for centering the coupler of the character illustrated in the drawings, yet as will be appreciated from the claims there are certain novel combinations and features of elemental construction which are entirely applicable to coupler centralizing devices of other forms.

I claim:

1. The combination with a car coupler having a head and stem, of a frame mounted upon said stem, and yielding means carried by said frame for centralizing said coupler, said frame involving separable members each of which is provided on its inner face with a projection, such projections being adapted to engage each other to constitute means for connecting said separable frame members laterally.

2. The combination with a car coupler having a head and stem, of a frame mounted upon said stem, and yielding means carried by said frame for centralizing said coupler, said frame involving separable members each of which is provided with a hook, said hooks being adapted to interlockingly engage each other.

3. The combination with a car coupler having a head and a stem, of a frame mounted upon said stem, and yielding means carried by said frame for centralizing said coupler, said frame involving separable members each of which is provided with a plurality of projections, the projections on one of said frame members being adapted to respectively engage and interlock with the mating projections on the other of said frame members, and some of said projections being disengageable upon movement in one direction and other of said projections being disengageable upon movement in a different direction.

4. The combination with a car coupler having a head and stem, of a frame mounted upon said stem, and yielding means carried by said frame for centralizing said coupler, said frame involving separable members

each of which is provided with a hook, the said hooks when in assembled relation being arranged one in advance of the other in interlocking engagement and constituting 5 means for connecting said separable frame members laterally.

5. The combination with a car coupler having a stem and a head removably mounted thereon, of a frame mounted upon said 10 stem, and yielding means carried by said frame for centralizing said coupler, said frame involving separable members and means adjacent to the coupler head for connecting said separable members, said connecting means being movable to and removable from assembled position in the direction of length of said stem.

6. The combination with the stem of a car coupler, of a coupler head removably 20 mounted on said stem, means for connecting said head and stem, a frame mounted upon said stem, said frame involving separable members, yielding means carried by said

frame for centralizing said stem, and means for connecting said separable frame members, said last named means being maintained in assembled position by the means for connecting the coupler head and stem. 25

7. The combination with a coupler having a head and stem, of a frame mounted upon said stem, and yielding means mounted upon and projecting through said frame for centralizing said coupler, said frame involving separable members and means for connecting the same, each of said separable 30 members having a plurality of projections one of which is a hooked projection, the hooked projections on the respective members being adapted to have interlocking engagement, and the other said projections being also adapted to respectively engage each other, and said means for connecting said separable frame members being spaced from 35 said hooked projections.

In testimony whereof I affix my signature. 40
WILLIAM KELSO.
